UNITED STATES PATENT OFFICE

LEONARD BOYD SPERRY, OF WESTERN SPRINGS, ILLINOIS, ASSIGNOR TO INTERNATIONAL HARVESTER COMPANY, OF CHICAGO, ILLINOIS, A CORPORATION OF ILLINOIS

LUBRICATING SYSTEM FOR CREAM SEPARATORS

Application filed May 28, 1924. Serial No. 716,301.

The present invention appertains broadly to cream separators and especially to a lubricating system for the operative parts thereof, whereby such parts are constantly drenched with a measured quantity of clean oil during their operation.

As is well known the operative parts of a cream separator are carefully machined and accurately dimensioned and are operated at a high rate of speed. Under these circumstances effective lubrication of all wearing parts assumes an important aspect. Because of the preciseness of the parts and their association, it is also important that only clean oil be utilized for lubricating purposes.

It is an object of this invention to provide a splash type of lubricator for cream separators and the like, the splash producing member picking up a measured quantity of only the clean, lighter oil from the oil containing casing, this being accomplished by the improved means hereinafter to be described.

A further general object is to provide a simple and efficient lubricating arrangement for cream separators, which is cheap to manufacture, and which is readily adapted for use with existing standard types of separators now on the market, at a minimum of expense.

Other objects will appear to those skilled in this art as the description progresses. The preferred embodiment of the invention has been well illustrated in the accompanying sheet of drawings wherein:

Fig. 1 is an approximately central, vertical sectional view of a cream separator taken along the line 2—2 of Fig. 2 and looking in the direction of the arrows;

Fig. 2 is a similar view looking in a direction at right angles to Fig. 1, with the base of the machine removed; and

Fig. 3 is a detail plan view of the supplemental reservoir or oil trough.

The preferred embodiment of the invention has been illustrated in association with a standard type of cream separator having a supporting frame 10 to which is bolted or otherwise suitably secured a gear housing 11, and integral with this housing is the usual

extension 12 for encasing, and within which is driven, the separating bowl (not shown). Journaled in suitable bearings formed in the upper part of the casing or housing 11 is a horizontal shaft 13 which carries at one end, 65 enclosed by a suitable casing, a gear 14 meshing with a pinion 15 keyed to a second horizontally disposed shaft 16, also journaled in suitable bearings in the housing 11. The shaft 16 has fixed thereto intermediately of 60 its ends, to operate substantially centrally within the gear housing 11, a gear 17 which meshes with a worm gear formed on a vertical spindle 18 supported in suitable bearings 19 and 20 carried, respectively, in the casing 11 65 and extension 12. The conventional hand operated crank 21 is disposed at the outer end of the shaft 13 for imparting rotation to the gear 14, pinion 15, gear 17 and spindle 18 to rotate rapidly the usual separating disks 70 forming the bowl of the separator (not shown).

The mechanism above described enables the spindle 18 to be driven at a very high rate of speed, and it is, therefore, essential that 75 each of these working parts be continuously lubricated so that friction will be reduced to a minimum. To this end, the lower part of the housing 11 receives, and is adapted to hold, a suitable supply of lubricating oil, as 80 shown in Fig. 2, which is maintained at a constant level by means of the overflow pipe 22 having a cap 23 slightly spaced therefrom and arranged thereover, so that excess oil may flow upwardly between the pipe 22 and cap 23 and out of the chamber by means of the drain pipe extension 24. Another drain pipe 25 depends from the bottom of the casing 85 for a purpose to be hereinafter described and supports a pail 26 in the manner shown 90 in Fig. 1.

Of course, it is of prime importance that all of the operative parts be continuously drenched in clean oil while operating, but it is of still greater importance, it has been 95 found, that they be drenched with a constantly fixed amount of oil. This invention takes cognizance of the fact that the clean oil is the lighter and less dense portion of the liquid and will naturally form at the top of 100

the oil bath, or at the point where the level of the bath is being maintained; and that the dirty and heavier, or denser, oil or impurities, such as milk or water, will precipitate to the bottom of the oil chamber below the maintained level of the bath. The lubricating system of the present invention is of the splash type and the problem is to splash only the clean, light and less dense oil in measured quantities from substantially the top of the bath onto the operative parts contained within the housing. The problem is solved by the provision of an elongated trough 27 disposed in a horizontal plane and resting at one end on a shoulder formed in the wall of the casing 11, and at its opposite end being bolted thereto, as shown in Fig. 1. This trough, it will be observed, has an arcuately shaped bottom and straight parallel sides between which operates the gear 17, the sides of the trough furthermore extending slightly above the maintained level of the oil bath. The bottom of the trough, it should be observed, is disposed in a plane a substantial distance below the maintained level of the oil in the oil chamber. Arranged centrally in the bottom of the trough is a small orifice 28, the clean oil from the top of the bath flowing upwardly therethrough into the trough and seeking a level coincident with the level of the bath in the chamber; thus, as the gear 17 is rotated, it splashes upwardly onto the operative parts of the mechanism only the measured amount of clean oil which has seeped upwardly into the trough, and, furthermore, the gear 17 does not have to contend with the resistance offered by the oil of the bath in the main chamber, thereby materially reducing the draft of the machine. The size of the orifice in the bottom of the trough will determine the rate of flow of oil into the trough, and the measured amount thereof to be maintained in the trough will be determined by the vertical distance between the bottom of the trough and the level of the oil in the main chamber. The heavier, dirtier and denser oil which has precipitated to the bottom of the bath may be easily drained therefrom by opening the petcock 29 at the terminal end of the drain pipe 25, this dirty oil being caught in the pail 26. Fresh oil is added to the chamber 11 by removing the spindle 18 and the separator bowl, not shown, and placing a funnel on the collar member 30, the oil then flowing downwardly past the bearing 20 and into the casing 11. This addition of fresh, clean oil will also automatically displace, by means of the overflow device, any dirt oil, water, or milk, not solidified, without resorting to use of the petcock 29.

A brief description of the operation of this improved lubricating system follows:

When the machine is in operation, upon rotation of the crank 21, the gear 17 rotates

very rapidly and picks up the measured amount of clean oil out of the trough 27, splashing it upwardly onto the shaft 13, the oil flowing along this shaft, as viewed in Fig. 2, to the right and to the left and seeping back into the chamber by means of the oil passages 31 and 32. Oil is also thrown on the spindle 18 and the bearings 20 and 19. A transparent sight panel 33 may be fitted to the casing adjacent the gear wheel 17, so that the operator may readily ascertain whether or not any oil is being thrown upon the operative parts mentioned. A constant liquid level is maintained by the overflow 22, and the dirty oil may be easily and expeditiously drained from the bottom of the oil chamber by means of the drain pipe 25, or it may be automatically forced out by adding fresh oil which will move the dirty oil from the bottom of the bath up between the cap 23 and pipe 22 and then out through the extension 24. When the machine is at rest only clean oil will be maintained in the trough, for any dirt particles will precipitate to the bottom and out through the orifice into the main oil supply.

It will thus be seen that there is herein provided lubricating apparatus in which the several objects of this invention are achieved and that the same is of simple construction, yet very effective in action, and is well adapted to meet the exacting conditions of hard practical use. While there has been shown the preferred embodiment of the invention, it is to be understood that various changes in form, construction and arrangement of parts may be made without departing from the spirit of the invention as claimed.

What is claimed is:

A cream separator having a case formed with a sump to receive a bath of lubricant, a vertically disposed spindle in the case adapted to carry a separator bowl, a gear in the case disposed in a vertical plane and adapted to drive the spindle, the gear dipping in the bath of lubricant, overflow means to prevent the oil from exceeding a predetermined level, and means for causing said gear to receive a constant, measured, restricted quantity of the lubricant for distribution thereby to the spindle.

In testimony whereof I affix my signature.

LEONARD BOYD SPERRY.
